United States Patent Office.

JAMES S. BODLE, OF MECKLENBURG, NEW YORK.

Letters Patent No. 62,596, dated March 5, 1867.

IMPROVEMENT IN INSTRUMENT FOR MARKING ANIMALS.

The Schedule referred to in these Letters Patent and making part of the same.

TO ALL WHOM IT MAY CONCERN:

Be it known that I, JAMES S. BODLE, of Mecklenburg, in the county of Schuyler, and State of New York, have invented a new and useful Improvement in Stamps for Marking Sheep, Cattle, Bags, &c.; and I do hereby declare that the following is a full, clear, and exact description of the same, reference being had to the annexed drawings, making part of this specification, in which—

Figure 1 is a side elevation.

Figure 2 is an end elevation; and

Figure 3 is a bottom view.

The same letters are employed in all the figures in the indication of identical parts.

The object of this invention is to furnish an adjustable brand or stamp to which different letters may be attached for the purpose of branding or printing, which is effected by the following arrangement of parts.

The frame is composed of two parts A and A¹. Their lower outside edges are made with an acute angle formed by beveling the bottoms and sides. At the top they have projecting from their inner and opposed faces lugs A² and A³. The lug A² is formed with horizontal and parallel faces. The lug A³ has its upper face horizontal and its lower face inclined at an obtuse angle to the inner face of the side piece A¹. B is the handle, attached to a stem, B', which has a thread cut upon it, working into corresponding female-threaded screws cut in holes through the lugs A² and A³. When the screw is turned so as to bring these lugs together, the upper edge of the point of the lug A², resting against the base of the lug A³, the point of the latter will be drawn down and the lower edge of the sides be thereby forced asunder. When the screw is relaxed they will approach one another. Metallic letters, C, are formed having notches bevelled on their upper faces inclined to correspond with the acute angle made by the edges of the side A and A¹, and at such distance from one another, that by relaxing the screw B', the sides A and A¹ will fall within the ends of the notches in the letters; but when the screw is tightened the edges of the sides will be forced into the notches in the letters, thus securely fixing them in place, as shown by the black and red lines in fig. 2.

What I claim as my invention, and desire to secure by Letters Patent, is—

1. A stamp or brand formed with an adjustable frame and movable letters, combined and arranged to operate substantially in the manner set forth.
2. The combination of the frame A A¹, with lugs A² and A³, threaded stem B', and notched movable letters C, substantially as set forth.

In testimony whereof I have signed my name to this specification in the presence of two subscribing witnesses.
